CLAIM

I claim the ornamental design for an organ chamber, as shown and described.

DESCRIPTION

FIG. 1 shows a perspective view of the closed organ chamber;

FIG. 2 shows a top view thereof;

FIG. 3 shows a bottom view thereof;

FIG. 4 shows a front view thereof;

FIG. 5 shows a side view thereof.

FIG. 6 shows a perspective view of the invention with the top open; and,

FIG. 7 shows an enlarged perspective view of the nozzle connection of the organ chamber shown separately for clarity.

The dash-dash broken lines depict portions of the invention that form no part of the claimed design.
